Attorney

UNITED STATES PATENT OFFICE.

JOSEPH EUCLIDE RICHARD, OF NEW BEDFORD, MASSACHUSETTS.

ADJUSTABLE FILLING GUIDE FOR SHUTTLES.

Application filed January 3, 1928. Serial No. 244,322.

This invention relates to new and useful improvements in loom shuttles and aims to provide an adjustable filling guide therefor. Through the medium of the present invention 5 the filling thread upon the bobbin within the shuttle is drawn therefrom in the proper manner, said guide applying the necessary tension to the thread or filling between the loom and the bobbin.

One of the foremost objects of the invention is to provide a filling guide of this character that may be adjusted for providing the proper tension to thread or filling of different characters, and when being used in different work.

A further object is to provide a guide that may be disposed within any conventional type of shuttle at the take off end of the bobbin without altering the construction of the 20 shuttle or without requiring any unusual expenditure.

In the drawing wherein like reference characters indicate corresponding parts throughout the several views:

Figure 1 is a fragmentary plan view of the threading end of a loom shuttle equipped with my improved adjustable filling guide.

Figure 2 is a transverse section taken substantially upon the line 2—2 of Figure 1 and looking in the direction of the arrows, and

Figure 3 is a perspective of the main elements of the present invention.

Now having particular reference to the drawing, A designates a generally conventional shuttle within which is a thread or filling bobbin B. My invention per se consists of a metallic clip 5 that is formed from a single length of suitable material that is bent intermediate its ends to provide a pair of spaced parallel legs 6—6 and a relatively wide bight portion 7, which bight portion is formed with a horizontal bottom wall within the center of which is an opening 8. This wall is adapted for disposition upon the bottom wall of the bobbin receiving portion of the shuttle A slightly forward of the bobbin end as indicated in Figure 1. Any desirable means may be provided for securing the clip to the shuttle, said means preferably consisting of a bolt and nut connection the bolt of which passes through the bottom wall of the shuttle and the opening 8 of the bight portion

of said clip 5, while threaded upon the inner end of the bolt within the bight portion is the nut as disclosed in Figure 2.

The invention further consists of a relatively wide length of frictional material, felt, or the like, designated by the reference character 9. The ends of the length of material are secured to the side walls of the shuttle 55 space holding the bobbin B through the medium of tacks or other fasteners. Intermediate these fastened ends the said material 9 is forced downwardly between the side legs 6—6 of the clip 5. Obviously the thread or 60 filling upon the bobbin B is drawn through the material 9 intermediate the side legs of the clip and the tension upon the thread or filling is regulated by the amount of pressure exerted by the clip side legs against the frictional 65 material. In order to adjust the guide to various work and to various filling the legs of the clip may be expanded by inserting a screw driver therebetween, or they may be forced together by gripping the same with a 70 pair of pliers or other instrument.

In view of the foregoing description when considered in conjunction with the accompanying drawings, it will be apparent that I have provided a novel, simple, inexpensive 80 but yet highly useful adjustable filling guide for loom shuttles that is well adapted for all the purposes heretofore designated, even though I have herein shown and described the invention as consisting of certain detail structural elements it is nevertheless to be understood that certain changes may be made therein without affecting the spirit and scope of the appended claim.

Having thus described the invention, what 90 I claim as new and desire to secure by Letters Patent is:—

In an adjustable filling guide for shuttles, a resilient U-shaped clip formed with a bight having a flat bottom wall and a pair of legs 95 converging inwardly toward each other, and terminating in spaced parallelism, a length of friction material arranged intermediate its ends between the legs of the clip, and at a point remote from said bottom wall, and means at the bight portion of the clip to permit of its anchorage to the shuttle.

In testimony whereof I affix my signature.

JOSEPH EUCLIDE RICHARD.
